UNITED STATES PATENT OFFICE.

PIERRE J. CHÉRON, OF NEW YORK, N. Y., ASSIGNOR TO TOWLE MANUFACTURING COMPANY, OF NEWBURYPORT, MASSACHUSETTS, A CORPORATION OF MASSACHUSETTS.

DESIGN FOR A HANDLE FOR SPOONS OR ANALOGOUS ARTICLES.

48,306.

Specification for Design.

Patented Dec. 21, 1915.

Application filed April 5, 1915. Serial No. 19,382. Term of patent 7 years.

To all whom it may concern:

Be it known that I, PIERRE J. CHÉRON, a citizen of the United States, residing at New York city, in the county of New York and State of New York, have invented a new, original, and ornamental Design for a Handle for Spoons or Analogous Articles, of which the following is a specification, reference being had to the accompanying drawing, forming a part thereof.

In the accompanying drawing, Figure 1 is a front elevation and Fig. 2 is a side elevation of a handle for spoons or analogous articles embodying my design.

I claim:

The ornamental design for a handle for spoons or analogous articles substantially as shown, or any colorable imitation thereof.

PIERRE J. CHÉRON.
